ATTORNEY.

UNITED STATES PATENT OFFICE.

IRA H. SPENCER, OF WEST HARTFORD, CONNECTICUT, ASSIGNOR TO THE SPENCER TURBINE COMPANY, OF HARTFORD, CONNECTICUT, A CORPORATION OF CONNECTICUT.

ROTARY BLOWER.

1,338,466.

Specification of Letters Patent.

Patented Apr. 27, 1920.

Application filed May 28, 1918. Serial No. 236,965.

To all whom it may concern:

Be it known that I, IRA H. SPENCER, a citizen of the United States, residing at West Hartford, in the county of Hartford and State of Connecticut, have invented a new and Improved Rotary Blower, of which the following is a specification.

My invention relates to the class of devices above named, and an object of my invention, among others, is to provide a device of this class that shall be simple but strong in construction and effective in operation.

One form of device embodying my invention and in the construction and use of which the objects herein set out, as well as others, may be attained, is illustrated in the accompanying drawing, in which—

The figure is a view in central vertical section through an apparatus embodying my invention.

In the accompanying drawing the numeral 5 indicates saddle supports having recesses to receive a shell 6 that is preferably round in cross section and generally cylindrical except for one end which is cut away at its upper part. This shell is made of comparatively thin metal and the cut-away end is reinforced and strengthened by ribs 7 secured against the inner and outer surfaces of the shell at the edge thereof. A cleat 8, of L-shape in cross section, extends around the lower portion of the cut-away end of the shell. A supporting ring 9 is secured against the inner surface of the shell a short distance from its cut-away end, and a partition plate 10, round and of dish-shape, is secured with its edge against the inner surface of the shell, at a short distance from the ring 9, thus creating a groove in which a packing 11 and a packing ring 12 are secured to effectually seal the joint between the partition 10 and the inner surface of the shell. The partition 10 creates a motor compartment 13 within which bed pieces 14 having curved lower edges to conform to the shape of the inner surface of the shell are secured. These bed pieces have flanges 15 to which rests 16 are secured, as by bolts, at the upper edges of the bed pieces. When secured by bolts, the latter may extend through the flanges of a motor 17 that is supported by the rests and within the compartment 13.

A two-part ring 18 is secured to the 55 bounding edge of an opening centrally through the partition plate 10, the facing surfaces of the ring being beveled to conform to the sloping surfaces of the partition plate, and as shown in Fig. 1 of the drawings. A spacing ring 19 having flanges at its opposite edges is secured against the inner face of the partition 10, this ring having that edge opposite to the partition plate located practically in the plane of the inner 60 face of the ring 18.

Fan chambers are located at intervals within the shell, each chamber having a discharge opening therefrom extending entirely around its periphery, said discharge 70 opening being narrower in width than the fan chamber. These fan chambers and discharge openings are created by a pair of double-walled structures, one wall or plate of each of which comprises a wall of the fan 75 chamber and the other wall or plate of each of which comprises a wall of the discharge opening, the last mentioned walls having beveled lips or flanges bounding the central openings through said plates comprising peripheral walls of the fan chambers.

One double-walled structure of a pair is smaller in diameter than the other, as herein shown, said smaller structure consisting of a fan chamber plate 20 and a discharge 85 opening plate 21 spaced apart but secured together by filling rings 22 secured in any desired manner, one ring being preferably located at the periphery of the plates, another one surrounding the beveled lip of 90 the central opening in the plate 21, and another located midway between those mentioned. The other and larger double-walled structure comprises a fan chamber plate 23 somewhat larger in diameter than the plate 95 20 and a discharge opening plate 24 somewhat larger than the plate 21 but otherwise of the same general shape. Filling rings 25 are located between the last mentioned plates in a manner similar to that above described with respect to the smaller double-walled structure.

An inner shell 26 surrounds all of the double-walled structures except those at the inlet discharge ends of the apparatus, said inner shell being spaced from the outer shell as by spacing rings 27. Annular corner pieces 28 are located in the corners between

the inner shell and fan chamber plates of the larger double-walled structures, and discharge vanes 29 are secured between the fan chamber plates of two adjacent double-walled structures, and in a return chamber between the sets or pairs of double walled structures. The discharge opening plate nearest the inlet end of the shell is enlarged as at 30, and lies between two flanged rings 31 extending entirely around the shell and secured together as by bolts passing through the flanges of the rings and through said enlarged portion of the discharge chamber plate. A packing may be suitably located 10 between these plates to prevent air passing through the joint. An end plate 32 similar in shape to the partition plate 10 is secured at the inlet end of the structure, an inlet tube 33 extending between and being secured 15 to the fan chamber plate and the end plate at this end of the structure, an L-shaped ring 34 joining the parts at the inner end of said tube and a two-part ring 35 having beveled meeting faces surrounding the central opening and receiving the edge thereat of the end plate 32. A clamping ring 48 for attachment of a conducting pipe may be secured to the ring 35.

A dish-shaped closing plate 36 is secured 20 to a fan chamber plate as by means of clips 37 located at intervals about the central opening through said plate. A shaft 38 projects from the motor through said plate and flanged hubs 39 are secured at intervals along the shaft and within the fan chambers. Fan supporting plates 40 are secured to the flanges of the hubs and fan blades 41 are secured to said plates at suitable intervals therearound. The plates 40 25 are preferably secured in place as by means of dish-shaped housings 42 inclosing the fan hubs and having openings closely fitting the shaft and outer lipped edges fitting the supporting plate. The parts may be secured 30 in any suitable manner, screws being shown herein for this purpose. A ring 49 is secured to the edges of the fan blades of each fan, said rings extending inward a short distance from the tips of the blades. These 35 tips are narrowed as by cutting off the corners, and the rings 49 and the supporting plates 40 have beveled flanges 50—51 to correspond in shape with the beveled ends of the blades.

55 A packing 43 is clamped between a closing plate 44 for the central opening in the partition plate 10 and a packing plate 45, the parts being secured together in any suitable manner, as by means of bolts and nuts 60 as shown herein. Said closing plate has a beveled edge fitting and resting against the sloping surface of the partition plate 10 at its inner edge and between the members of the two-part ring 18 by means of which the 65 closing plate is secured in place. A port 46

extends through the wall of the shell at the outlet end thereof, and a tube extension 47 is secured to the outer surface of the shell surrounding said opening to conduct the currents of air that pass through said opening. 70

A packing 52 is located between the spacing rings 27 and a spacer 53 is located between said rings to properly separate them. While the apparatus embodying my invention is named a blower herein, it will be understood that the invention is present whether the device be employed to increase or reduce pressure at any point, and in accordance with the provisions of the patent 75 statutes, I have described the principles of operation of my invention, together with the apparatus which I now consider to represent the best embodiment thereof; but I desire to have it understood that the apparatus shown is only illustrative, and that the invention may be carried out by other means. 80

I claim—

1. A blower comprising a shell, two double-walled partitions located within the shell and forming a fan chamber between them, the walls of each partition being separately formed each from the other and of substantially uniform thickness throughout, a shaft supported within the shell, and a fan secured to said shaft and located within in said chamber. 90

2. A blower comprising a shell, two double-walled partitions located within the shell and forming a fan chamber between them, the walls of each partition being separately formed each from the other and of substantially uniform thickness throughout, 95 spacers located between said double walls, a shaft supported within the shell, and a fan secured to said shaft and located within in said chamber. 100

3. A blower comprising a shell, discharge openings and return chambers alternately arranged lengthwise of the shell, the partitions between said chambers comprising double-walled structures, each of said walls being separately formed from the other and both being of substantially uniform thickness throughout, means for separating the double walls of each partition, a shaft supported within the shell, and a fan secured to said shaft and located within fan chambers opening into the discharge chambers. 110

4. A blower comprising a shell, two double-walled partitions located within the shell and forming between them a fan chamber with a discharge opening therefrom, the walls of each partition being separately 125 formed each from the other and of substantially uniform thickness throughout, one member of each of said double walls having a beveled lip at the entrance to said discharge opening, a shaft supported within 130

the shell, and a fan secured to said shaft and located in said chamber.

5. A blower comprising a shell, two double-walled partitions located within the shell and forming a fan chamber between them, one of each of said double walls having its inner edge located nearer the axis of the shell than the other double wall and comprising one wall of a fan chamber, and the 10 other of each of said double walls comprising one wall of a discharge opening, a shaft supported within the shell, and a fan secured to said shaft and located in said chamber.

15. 6. A blower comprising a shell, two double-walled partitions located within the shell and forming a fan chamber between them, spacers concentrically arranged and separated between the members of each double-wall, one member of each double wall having its inner edge located nearer the axis of the shell than the other member of said wall and comprising one wall of a fan chamber, and the other member of each of said 20 double walls having a beveled lip at its inner edge, a shaft supported within the shell, and a fan secured to said shaft and located in said chamber.

25. 7. A blower comprising a shell, two double-walled partitions located within the shell, the walls of each partition being separately formed each from the other and of substantially uniform thickness throughout and one member of each double-walled partition forming one wall of a discharge opening from a fan chamber and the inner edges of said walls being flared outwardly within the fan chamber, a shaft supported within the shell, and a fan secured to said shaft 30 and located in said chamber.

40. 8. A blower comprising a shell, a plurality of pairs of double-walled partitions located within the shell, the walls of each partition being separately formed each from the other and of substantially uniform thickness throughout and one member of each pair being larger than the other, discharge 45 vanes located between the smaller and larger member of adjacent pairs of partitions, a shaft supported within the shell, and a fan secured to said shaft and located in said chamber.

50. 9. A blower comprising a shell, a plurality of sets of double-walled partitions, each set comprising a partition of lesser diameter than the other partition, curved corner plates located at the corners between the inner surface of the shell and each of said larger partitions, a shaft supported within the shell, and a fan secured to said shaft and located in said chamber.

60. 10. A blower comprising a shell, a plurality of sets of double-walled partitions, each set comprising a partition of lesser diameter than the other partition, one mem-

ber of adjacent double-walls being flared away from the other member, and the other member of adjacent walls extending nearer the axis of the shell than said flared members, spacers located between the double-walls, curved corner plates located at the corners between the inner surface of the shell and edges of said larger partitions and curving over the edge of a smaller partition, a shaft supported within the shell, and 70 a fan secured to said shaft and located in said chamber.

75. 11. A blower comprising a shell, two double-walled partitions located within the shell, the outside members of each of said double walls extending inwardly beyond the inside members thereof and forming the walls of a fan chamber, and the inner members of said double walls comprising the walls of a discharge opening narrower in 80 width than said fan chamber, a shaft supported within the shell, and a fan secured to said shaft and located in said chamber.

85. 12. A blower comprising a shell, a plurality of double-walled partitions located within the shell, one being larger in diameter than the others and secured at the end of the shell, an inner shell spaced from the outer shell and resting against the edge of a double-walled partition less in diameter than said end partition, an intermediate double-walled partition less in diameter than either of those first mentioned and forming with the end partition a fan chamber and a discharge opening, a shaft supported within the shell, and a fan secured to said shaft and located in said chamber.

90. 13. A blower comprising a shell, a plurality of double-walled partitions located within the shell, one of said partitions being larger in diameter than the others and secured at the end of the shell, an inner shell, spacing rings located between the inner and outer shells, a packing located between said rings, a double-walled partition 95 located within the inner shell and less in diameter than said end partition, an intermediate double-walled partition less in diameter than either of those first mentioned and forming with the end partition a fan chamber, discharge vanes located between the partition of least diameter and that of the intermediate diameter, a shaft supported within the shell, and a fan secured to said shaft and located within the fan chamber.

100. 14. A blower comprising a shell, partitions located within said shell, each comprising a double wall with one wall forming part of a fan chamber and the other part of a discharge opening from said fan chamber, the walls of each partition being separately formed each from the other and of substantially uniform thickness throughout and rigidly secured together by spacers located between them, the inner edges of the 105

120

125

130

walls of the discharge chamber being flared outwardly within the fan chamber, a shaft extending into the fan chamber, and a fan comprising blades having their outer edges narrowed to conform to the flared edges of the walls of said partitions.

15. A blower comprising a shell, partitions located within the shell, each comprising a double wall, one wall of which forms one 10 wall of a fan chamber and the other wall of which forms one wall of a discharge opening, the inner edges of the walls of the discharge chamber being flared within the fan chamber, a shaft extending within the fan 15 chamber, and a fan secured to said shaft and comprising a supporting plate having a beveled flange to conform to the flaring edges of said walls, fan blades secured to the plate and having their ends conforming 20 to the beveled flange of said plate, the opposite edges of said blades being also beveled at their tips, and a ring secured to the outer edges of said blades and having its outer edge beveled to correspond to the shape of 25 the beveled ends of said blades and to conform to the flared edges of said walls.

16. A blower comprising a shell, a dish-shaped plate forming one wall of a chamber within the shell and having a central 30 opening, a two-part ring having sloping facing surfaces and secured on opposite sides of said plate at the edge of said opening, means for supporting said two-part ring, a shaft supported within the shell, and a 35 fan secured to said shaft.

17. A blower comprising a shell; a dish-shaped plate dividing the shell into two compartments and having an opening at its center, a plate to close said opening and having a beveled edge to conform to the sloping surface of the dish-shaped plate, a two-part ring having sloping facing surfaces secured to the opposite sides of said dish-shaped plate and said closing plate, a shaft 40

supported within the shell, and a fan supported to said shaft.

18. A blower comprising a shell, two double-walled partitions located within the shell and forming a fan chamber between them, one member of each of said double 50 walls having its inner edge located nearer the axis of the shell than the other member of said double wall and comprising one wall of a fan chamber, and the other member of each of said double walls having a 55 central opening with the edge thereof flared outwardly to form a peripheral wall of said fan chamber, a shaft supported within the shell, and a fan secured to said shaft and located in said chamber.

19. A blower comprising a shell, two double-walled partitions located within the shell and forming a fan chamber between them, spacers concentrically arranged and separated between the members of each 60 double wall one member of each double wall having its inner edge located nearer the axis of the shell than the other member of said wall and comprising one wall of a fan chamber, a shaft supported within the 65 shell, and a fan secured to said shaft and located in said chamber.

20. A blower comprising a shell, a plurality of double walled partitions located within the shell, one being larger in diameter than the other, an inner shell spaced from the outer shell and inclosing said larger partition that is secured at its edge to the inner surface of said inner shell, a smaller partition located within the inner 70 shell and having its edge spaced from the inner surface of said inner shell, said smaller partition forming one wall of a fan chamber, a second wall for said fan chamber, a shaft supported within said blower, 75 and a fan secured to said shaft within said fan chamber.

IRA H. SPENCER.
